(57) **CLAIM**

The ornamental design for a bridge top, as shown and described.

DESCRIPTION

FIG. 1 is an isometric view of the bridge top of the present invention as a whole.

FIG. 2 is a top view of the bridge top of the present invention in plan.

FIG. 3 is a side view of the bridge top of the present invention.

FIG. 4 is a side view of the right edge of the bridge top of the present invention.

FIG. 5 is a back view of the bridge top of the present invention; and,

FIG. 6 is a back view of the left edge of the bridge top of the present invention.

The bridge top has a top with a specifically designed geometric shape with a straight flat edge at the back, one curved edge at the front which has a profiled shape, and two curved edges at the sides which have a counter-profiled shape.
